GROUND CLAMP

James Mangin, New Brunswick, N. J., assignor
to New Brunswick Electric Supply Company,
New Brunswick, N. J., a corporation of New
Jersey

Application January 9, 1930. Serial No. 419,598

3 Claims. (Cl. 247—1)

The present invention relates to ground clamps such as are used in the installation of electric wiring in buildings to ground to a water pipe and the like the lead-in conduit and the conductor 5 or conductors carried thereby and, particularly, relates to improvements in said ground clamps whereby universal adjustment of the clamp may be made to connect it to a grounding pipe and an electric conduit regardless of the direction of 10 approach of the conduit relative to the grounding pipe without necessitating the removing and replacing of any of the parts of the clamp to make such adjustments.

The principal object of the invention is to provide a ground clamp which may be attached to a water pipe and the like and then positioned to receive an electric conduit which may approach the grounding pipe from any direction relative to the pipe.

Another object is to provide a clamp which may be attached to pipes of various diameters and still provide a very rigid and efficient connection between the conduit and the conductor to be grounded and the grounding pipe.

Another object is to provide a clamp which may be attached to pipes of various diameters and which is provided with means for adjusting itself to the particular diameter of pipe used without taking the clamp apart.

A further object is to provide a ground clamp in which the clamping means serves to hold the various elements of the clamp in rigid assembled relation and simultaneously provides a direct efficient electrical connection between the grounding pipe and the conductor to be grounded.

A still further object is to provide a clamp in which the clamping means serves to hold the various elements of the clamp in rigid assembled relation after the adjustments are made and simultaneously provides efficient electrical connections between the grounding pipe, the conduit and the conductor to be grounded.

Other objects and advantages will appear more fully hereinafter from the following detailed description taken together with the accompanying drawing, in which:

Fig. 1 is an end view of my device clamped to a grounding pipe;

Fig. 2 is a sectional view thereof taken along the line 2—2 of Fig. 1;

Fig. 3 is a perspective view of the conduit-receiving element;

Fig. 4 is a perspective view of the clamp element;

Fig. 5 is a sectional view of a modification of the assembled clamp; and

Fig. 6 is a perspective view of a preferred terminal lug used in connection with my device.

Referring to Figs. 1 to 4, the device comprises the clamping element 1 which is provided with a circular base portion 1a having a pair of diametrically-opposed recesses 8. Extending from the base 1a and integral therewith are a pair of uprights 2 disposed in parallel relation which are joined on one side by a wall 3 extending between them and holding them in spaced relation. The other side is left open to form a recess 4 combining with the recess 8 to provide for the reception of the S-bolt 15, as will be explained more fully hereinafter. The recesses 8 are provided for the reception of the shanks of a U-bolt, as shown in the modification in Fig. 5. Each upright 2 has a U-shaped recess extending therein which forms a pair of jaws for gripping the pipe 17 and each jaw is provided with portions 5, 6 and 7 which in the present instance are made up of arcuous portions of surfaces of cylinders of various diameters so that no matter what the diameter of the pipe 17 may be, it may be placed in the jaw and still make efficient contact with the jaws. For example, as shown in Fig. 1, the diameter of the pipe 17 is such that it contacts with the portions 6 of the jaws; if the pipe were of a smaller diameter, it would be seated in the portion 5 and if larger in diameter, would contact with the portions 7. In this way, the device may be clamped to a pipe of any diameter within the constructional limits of the device. The conduit-receiving element 9 is provided to co-act with the base 1a of the clamping element 1 and is also circular in form and of the same diameter as the base 1a, so that it may coincide therewith when assembled, as shown in Figs. 1 and 2. It is provided with a central opening 14 through which the shank of the S-bolt is adapted to pass to receive the terminal lug 19 to which is attached the conductor 23 extending from the conduit 24. Integral with the circular or disk portion of the element 9 is a cylindrical portion 10 having its axis perpendicular to the axis of the disk and is threaded at 11 for the reception of the electrical conduit to be grounded which carries the conductor or conductors 23 also to be grounded. Crescent-shaped recesses 12 are provided so that the element may be rotated about its axis when a U-bolt is used to clamp the pipe, the shanks of the U-bolt extending through these recesses, (Fig. 5). The clamping element 1 and the conduit-receiving element 9 are held together 110

in cooperating relation by means of the S-bolt 15 (Figs. 1 and 2) which serves the purpose of holding the assembled clamp rigidly to the pipe 17 simultaneously and provides electrical connections for the terminal lug 19 by means of the washer 18' and the nut 18. The conduit 24' is grounded through element 9 and the clamping element 1. When the nut 18 is drawn up and tightened on the shank 16, the entire assembly 10 becomes rigid and provides an efficient electrical connection between the conductor, the conduit, and the grounding pipe. To connect the clamp to a pipe, the S-bolt 15 is inserted in the opening 14 of the element 9 and the clamping element 15 is placed in juxtaposition with the element 9 so that the shank of the bolt passes through the recess 4 and the uprights 2 are then placed against the pipe so that the pipe may be seated in the curved portions 5, 6 or 7, depending on its 20 diameter and the hook portion of the S-bolt is made to engage the pipe and then the conduit is screwed into the cylindrical portion 10 of the element 9 and the conductor 23 which extends from the conduit 24' is attached to the shank 16 of the bolt 15 by means of the terminal lug 19. The washer 18' is then placed on the shank to provide a more rigid connection of the terminal lug and the nut 18 is then drawn up and tightened against the washer 18'. It will be seen that 30 this arrangement of parts provides an adjustment of the clamp while it is attached to the pipe 17 to receive the conduit 24' from any direction relative to the direction of the pipe. For example, in Fig. 2, the conduit 24' is shown as approaching the pipe 17 from the right, and parallel to it. If the conduit approached the pipe from the left, all that would be necessary to connect the clamp to the conduit would be to rotate the conduit-receiving element 9 about the shank 16 of the bolt 15 until the portion 10 would come into alignment with the conduit. Or, if the conduit approached the pipe from directions perpendicular to the direction of the pipe, it still could be connected to the clamp by 40 rotating the element 9 as before. If the conduit approached the pipe from a direction which would be in some other plane, it would then be necessary to rotate the entire assembly about the pipe 17 until the proper position is reached and then rotating the element 9 about the bolt 15 to bring the portion 10 in alignment with the conduit 24'. This may be accomplished without removing 50 the clamp from the pipe or any of the parts of the clamp and having to replace them after the adjustment is made.

In Fig. 5 is shown a modification in which a U-bolt 25 is substituted for the S-bolt 15 and a separate carriage bolt 29, threaded at 28, is provided for connecting the conductor 23 to the clamp. In this modification, the hole 14 is square instead of round in order to prevent the bolt 29 from turning when the nut 30 is drawn up and tightened on it. The shanks 26 of the U-bolt extend through the crescent-shaped recesses 12 of the element 9 and the bolt is made to engage the pipe 17 firmly by the nuts 27 which are drawn up and tightened on the shanks and also serve to clamp the conduit-receiving element 9 against the clamping element 1. In this

modification, the element 9 may still be rotated about the bolt 29 without interfering with the shanks 26 of the bolt 25, since clearance is provided for them by means of the recesses 12. The same adjustments may be made as when the S-bolt is used.

In Fig. 6, I have shown an improved terminal lug for connecting the conductor 23 to the shank of the S-bolt in Fig. 2 or the bolt 28 in Fig. 5. The lug is stamped out of some conducting material, preferably copper, and is provided with a pair of holes 20 and a hole 22 for the reception of the conductor 23 as indicated. When the hole 22 is cut out, the material which is removed from the hole is not cut away completely but is turned up in the form of triangular prongs 21 which are adapted to engage the conductor 23 when it is passed through the holes 20. The conductor is inserted by passing one end of it through one of the holes 20 and bending it around the portions 21 which are normally vertical and then inserting it into the other hole 20. The prongs 21 are then bent over the conductor and, in this way, a rigid and efficient contact is made between the lug and conductor and a soldering operation is thereby eliminated. The hole 22 is provided for the reception of a connecting bolt.

While I have shown only two embodiments of my invention for the purposes of illustration and description, other changes and modifications may be made therein without departing from the scope of the invention and I, therefore, desire to be limited only by the scope of the appended claims.

I claim:

1. A ground clamp for connecting a conductor of an electric conduit to a grounding means, comprising a recessed clamping element having parallel recessed walls for receiving said grounding means, a conduit-receiving element having an opening therein, and a clamping bolt embracing said grounding means and extending between said walls and through said opening for attaching said elements together and to said grounding means.

2. In a ground clamp for connecting a conductor of an electric conduit to a grounding means, a clamping element having parallel recessed walls for receiving said grounding means and a base recessed at its sides for receiving a clamping U-bolt, the shanks of said bolt extending between said walls, and a conduit-receiving element having arcuate side openings aligning respectively with said recesses for receiving said bolt, whereby said conduit-receiving member may be rotated about said bolt.

3. In a ground clamp for connecting a conductor of an electric conduit to a grounding means, a clamping element having parallel recessed walls for receiving said grounding means and a base recessed centrally for receiving a clamping S-bolt, the shank of said bolt extending between said walls, and a conduit-receiving element having a central opening aligning with said recess for receiving said bolt, whereby said conduit-receiving member may be rotated about said bolt.

JAMES MANGIN.
